[57] CLAIM

The ornamental design for a telescopic sight mount for pistol, as shown and described.

DESCRIPTION

FIG. 1 is a prospective view of a telescopic sight mount for pistol showing my new design;

FIG. 2 is a side elevational view of the mount;

FIG. 3 is a top plan view of the mount;

FIG. 4 is a bottom plan view of the mount;

FIG. 5 is a front elevational view of the mount; and

FIG. 6 is a rear elevational view of the mount.

*Fig. 1.**Fig. 2.**Fig. 3.**Fig. 4.**Fig. 5.**Fig. 6.*
